FAUCET FOR MEASURING, MIXING, AND DISPENSING BEVERAGES

John H. Donnelly, New York, N. Y., assignor to Canada Dry Ginger Ale, Incorporated, New York, N. Y., a corporation of Delaware

Application October 20, 1948, Serial No. 55,488

2 Claims. (Cl. 222—133)

1

The present invention relates to a combined mixing and measuring faucet for use in dispensing carbonated beverages or the like, and aims to provide certain improvements therein.

Prior devices of the type specified have been costly and complicated in construction, have been difficult to take apart for cleansing purposes and then reassemble, and lacked many other desirable qualities that a dispensing faucet should have.

Accordingly, my invention has among its objects (1) to provide a faucet which will be simple in construction and adapted to be taken apart for cleansing purposes and reassembled without the aid of special tools or special mechanical skill; (2) to provide a faucet of the type specified by means of which carbonated water and a flavoring liquid can be dispensed in definite proportions regardless of the volume of the drink to be served; (3) to provide such faucet which will thoroughly mix the carbonated water and flavoring liquid prior to discharge and thus eliminate the need for stirring the prepared drink; (4) to provide such faucet in which afterdrip from the faucet is eliminated; (5) to provide such faucet, which by a slight movement of the operating handle, flavoring liquid only may be dispensed for sundaes, toppings, etc.; and (6) to provide such faucet which will have none of its operative parts exposed to contaminating influences.

The foregoing and other objects of my invention not specifically enumerated I accomplish by providing a dispensing faucet in which control valves for the flavoring liquid and the carbonated water are mounted in coaxial relation and are operable in sequence by a single draft arm so as to be substantially simultaneously operable; wherein by virtue of said sequential operation, flavoring liquid only may be dispensed, if desired; wherein a flavoring liquid chamber is provided which is adapted to hold a predetermined quantity of flavoring liquid necessary to produce a predetermined volume of carbonated beverage of uniform composition; wherein the passages are calibrated for dispensing the flavoring liquid and the carbonated water in definite proportions when a drink of smaller volume is to be prepared; wherein the faucet is so constructed that the predetermined quantities of flavoring liquid and carbonated water are thoroughly mixed before discharge into the container from which the beverage is to be consumed; and wherein the constituent elements of the faucet are mounted in coaxial relation to facilitate disassembly of the parts for cleansing purposes and reassembly.

2

without the need for any special tools or mechanical skill. The invention also embodies other features of novelty and combination of parts all of which will be better understood from the detailed description which follows, when considered in connection with the accompanying drawings, wherein:

Figure 1 is a substantially diametrical section through a faucet embodying my invention, mounted in position on a fountain support, the upper portion of said figure being a section taken along the plane of the line 1—1 of Fig. 2.

Fig. 2 is a transverse section taken substantially along the plane of the line 2—2 of Fig. 1.

Fig. 3 is a section taken substantially along the plane of the line 3—3 of Fig. 1.

Fig. 4 is a section taken substantially along the plane of the line 4—4 of Fig. 1.

Fig. 5 is an elevation of a detail of the invention.

Referring to the drawings, the mixing and measuring faucet is designated as a whole by the reference numeral 10 and may be said to comprise a housing consisting of a head member 11, a flavoring liquid chamber providing member 12 and a spout member 13, said members being of generally cylindrical form and detachably connected together in coaxial relation. The faucet may be supported in any preferred manner and as shown is supported and connected by screws 14 to a frame 15, which may be mounted on the rail of a serving fountain (not shown), which, in turn, may also support a flavoring liquid reservoir 16 with its base preferably above the flavoring liquid ingress duct to the faucet so that said liquid may be fed to the faucet by gravity.

The head member 11 is formed with an axial bore therethrough of different diameters 17, 18 and 19, there being provided an internal flange 20 between the bores 17 and 18, the upper surface of said flange constituting a valve seat for a check valve 21 which is normally held upon said seat by a spring 22 bearing at one end against the valve body and at its other end against a shoulder within a closure plug 23 which is screw-threaded into the bore 17. The check valve 21 also has a pin 24 extending through the opening provided by the flange 20 for a purpose which will be presently described. Extending radially through the head member 11 is a duct 25 terminating at its inner end in the valve chamber provided by the bore 17 and being enlarged and screw-threaded at its outer end, as indicated at 26, for accommodating a coupling nipple such as 27 to which is connected a conduit 28 through

which carbonated water may be supplied to the faucet. Both axially and angularly spaced from the duct 25, the head member is formed with a screw-threaded radial opening 29 within which is connected a coupling nipple 29a having a conduit 30 attached thereto through which a flavoring liquid from the reservoir 16 is supplied to the faucet. Dependently supported by the head member 11 by means of a screw-threaded connection in the bore 18 is a cylindrical tube 31 which extends through the chamber-providing member 12 and into the spout member 13, the lower external diameter of the tube being of reduced diameter as shown at 31a, for a purpose presently to be described.

The chamber-providing member 12 at its upper end is formed with a reduced externally screw-threaded portion 32 for accommodating a locking ring 33, by means of which the head member 11 is connected to the member 12. For facilitating said connection, the member 11 has a flange 34 and a pilot end 35. The member 12 has an enlarged bore 36, a reduced bore 37 and a shoulder or base 36a therebetween, the diameter of the bore 37 being exactly the same as that of the bore 19 in the head member 12, for a purpose which will presently appear. At its lower end the member 12 is formed with a reduced, externally screw-threaded portion 38 and an internally rabbeted groove 39 for accommodating the pilot end of a connecting sleeve 40 screw-threadedly carried by the spout member 13 and through which connecting sleeve the spout member is detachably held to the chamber-providing member 12 through a locking ring 41.

The spout member 13 is of generally hollow, cylindrical form having a cylindrical bore 42 terminating at its lower end in a conical seat 43, and on its exterior is formed with an enlargement 44 providing a bearing for an oscillatable stub shaft 45 carried by an operating handle or draft arm 46. The shaft 45 is formed with a tooth 47 projecting into the bore 42 and adapted for limited angular movement around the axis of the shaft 45, for a purpose which will presently appear. The shaft 45 may be suitably held within the bearing portion of the spout member by a washer 48, a packing 49 and an internal locking nut 50, as shown in Fig. 4.

Mounted within the faucet for axial movement relatively to the housing is a cylindrical sleeve 51 having an external diameter equal to the internal diameter of the bores 19, 37 and 42 and an internal diameter equal to the full external diameter of the hollow tube 31. The sleeve 51 intermediate its ends is cut away to provide arcuate slots 52 and is formed with an external annular groove 53 in proximity to its lower end, and with aligned radial holes 54 in still closer proximity to said end. The sleeve 51 is mounted so as to constitute a slide valve for controlling the ingress and egress of flavoring liquid to and from the chamber provided by the bore 36 and base 36a of the member 12 and is manually operable by the handle 46 by virtue of the tooth 47 on the operating handle shaft 45 engaging within the annular groove 53. The sleeve 51 is normally held in its lowermost position by a helical spring 55 one end of which bears against a shoulder provided by the under side of the flange 20 and the other end bears against an abutment such as a nut 56 threaded on a stem 57, the lower end of which carries a cross-pin 58 which engages in the aligned radial holes 54. If desired, a valve 59 may be mounted at the lower end of the stem

57 for seating against the conical seat 43 in the spout member. Mounted at the top of the stem 57 is a mushroom shaped head 61 having an axial recess 62 into which slidably fits the pin 24 of the check valve 21, the depth of said recess being such that the lower end of the pin 24 will be engaged and moved to unseat the valve after a predetermined amount of movement of the stem 57. Of course, the extent of upward movement of the stem 57 should be sufficient to cause engagement of the head 61 with the flange 20, and such movement may be limited by engagement of the head 21a of check valve 21 with the closure plug 23.

The sleeve 51 in its normal position has its top below the bottom of the bore 19 in the member 11 and its arcuate slots 52 below the bottom wall 36a in member 12. In said position it will be apparent that flavoring liquid from the reservoir 16 may enter through the coupling nipple 29a and bore 19 into the chamber defined by the bore 36, the external wall of the sleeve 51 and the base 36a in the member 12 and fill said volume. As the operating handle is moved upwardly it moves the sleeve 51 upwardly so that the top portion thereof snugly engages into the annular space between the bore 19 and the exterior wall of the upper portion of the hollow tube 31, closing off admission of flavoring liquid into the chamber and at the same time bringing the arcuate slots 52 above the base 36a of the chamber, thus permitting the egress of the liquid from said chamber through said slots down past the annular space between the exterior surface 31a of reduced diameter of the hollow tube 31 and the internal bore of the sleeve 51 into the spout member. Preferably the check valve 21 is so related to the stem 57 as to open after the opening of the flavoring liquid discharge valve 52, although the time sequence of the opening of said valves may be in such rapid sequence brought about by a quick upward movement of the operating handle so that the opening of said valves may be considered to be substantially simultaneous. It will be appreciated, however, that if desired, only flavoring liquid may be dispensed for use on sundaes, toppings, etc., by controlling the upward movement of the operating handle 46 so as not to unseat the valve 21.

In dispensing flavored drinks at a fountain it is highly desirable that the resulting beverage be of uniform strength especially so where a well known advertised brand of beverage is being so dispensed. Accordingly, it is essential that the discharge rate of flow of the flavoring liquid to the carbonated water should take place in a definite proportion. With the faucet of the present invention this is accomplished by calibrating the annular space between the external surface 31a of the tube 31 and the internal surface of the sleeve 51 to bear a definite relation to the size of the duct 25 in the head member 11 and the pressure usually employed in supplying the carbonated water to the faucet. By having the flavoring liquid dispensed from the chamber 12 which is pre-filled, the flow rate of said flavoring liquid from said chamber will be substantially uniform as it is not dependent upon the gravity head of the flavoring liquid in its reservoir 16, the height of which will vary considerably depending upon the quantity of flavoring liquid therein. As the last remaining portion of flavoring liquid drains from the chamber 12 there would be a tendency for such liquid to be held by capillary action in the annular space be-

tween the external surface 31a of tube 31 and the internal surface of the sleeve 51, but such tendency is overcome by the venturi effect created by the carbonated water issuing from the discharge end of the tube 31.

By referring to Fig. 1 of the drawings it will be noted that the discharge ends of the tubes through which the flavoring liquid and the carbonated water enter the spout member are above the discharge end of the spout and also that when the valve 59 is open, the upper conical surface 59a thereof will act as an abutment against which the discharging liquids will impinge prior to passing out of the faucet. In view of the charged condition of the water, a thorough mixing of the water and flavoring liquid will thus take place within the spout member of the faucet prior to discharge. The volumetric capacity of the chamber in the member 12 also bears a definite relation to the rate of flow of the carbonated water such that the complete emptying of said chamber in the drawing of a beverage will be in accordance with the predetermined proportion of the flow of the liquids from the faucet.

The flavoring liquid may be supplied by gravity or by pressure fed to the faucet through the conduit 30 and is preferably pre-cooled prior to admission to the faucet. The carbonated water should likewise be pre-cooled and supplied to the faucet under pressure. Where gravity feed of the flavoring liquid to the chamber is relied upon, it is apparent that the liquid will not flow into or out of said chamber unless an air vent is provided through which air may leave the chamber as liquid enters the same, and vice versa. Accordingly, the faucet is herein shown as provided with a vent passage 65 extending through the head member 11 and leading through a conduit 66 to the top of the flavoring liquid reservoir 16 which is open to atmospheric pressure.

From the foregoing detailed description it will be appreciated that the construction and operation of my improved faucet is simple and that it may be taken apart and reassembled without the aid of special tools or mechanical skill, for example, by merely disconnecting the nipples 27 and 29 and unscrewing the locking rings 33 and 41, the complete faucet may be disassembled for cleansing purposes. In the alternative, the faucet may be thoroughly cleansed by merely discon-

necting the coupling nipple 29a and connecting to the faucet a hose leading from a hot water line which will serve to thoroughly wash out the faucet.

5 Although I have shown and described a preferred embodiment of my invention, it will be understood that changes in the details of construction of the faucet may be made within the range of mechanical and engineering skill without departing from the spirit of my invention as defined in the appended claims.

What I claim is:

1. A stationary beverage dispensing device comprising a housing having therein a chamber 15 providing a substantially fixed hydrostatic pressure for flavoring liquid, said chamber having an inlet passage and an outlet passage, a slide valve within the housing movable to substantially simultaneously open one of said passages and close the other of said passages, a duct for carbonated water concentrically disposed in relation to the chamber, a normally closed spring-seated valve controlling said duct, said slide valve and spring-seated control valve being concentrically disposed, 20 25 a discharge spout below both said chamber and said duct, and a single means for operating said valves.
2. A stationary beverage dispensing device comprising a housing having therein a flavoring liquid chamber having an inlet and outlet passage, a slide valve within the housing movable to substantially simultaneously open one of said passages and close the other of said passages, a duct for carbonated water concentrically disposed in relation to the chamber, a normally closed spring-seated valve controlling said duct, 30 35 said slide valve and spring-seated control valve being concentrically disposed, a discharge spout below both said chamber and said duct, and means for substantially simultaneously operating said valves.

JOHN H. DONNELL.
